UNITED STATES PATENT OFFICE.

HENRY E. WEBER, OF CANTON, OHIO.

DENTAL TRAY.

Application filed May 11, 1921. Serial No. 468,610.

To the Commissioner of Patents:

Be it known that I, HENRY E. WEBER, a citizen of the United States, residing in the city of Canton, county of Stark, and

5 State of Ohio, have invented certain new and useful Improvements in Dental Trays, of which the following is a specification.

The invention relates to trays for supporting dental instruments and like appliances, and the object of the improvement is 10 to provide a supporting bracket upon which a tray can be removably mounted, with yielding seating means for holding the tray firmly in place without the use of locks or 15 latches.

Dental trays are frequently made round in form of fragile material with a shallow curved rim provided with grooves for receiving the stems or handles of instruments, 20 and it is common practice to support the same upon brackets having a central pivotal stem with radial arms engaging the rim of the tray, with a latch on one of the arms for locking the tray in position.

25 It is also common practice for a dentist to use two or more trays, each carrying a set of instruments so that one set may be sterilized while another set is being used, and in such event the removal and replacement of a tray is of frequent occurrence and the opening and closing of a locking latch not only consumes time and attention, but unless its clamping action is carefully controlled, it is sometimes injurious to and may 35 be destructive of the tray.

These difficulties are overcome in the present improvement by forming upwardly curved radial seats at the ends of the arms for supporting and surrounding the rim 40 portion of the tray, and by providing the same with resilient radial ribs for cushioning and clamping the curved rim portion of the tray and holding it firmly in position thereon, while permitting a ready removal therefrom.

A preferred embodiment of the invention is illustrated in the accompanying drawings, forming part hereof in which—

Figure 1 is a plan view of a bracket, 50 showing the tray thereon in broken lines;

Fig. 2, an elevation section of the same on line 2—2, Fig. 1; and

Fig. 3, an enlarged section of the rim of

the tray on the same line, showing a side elevation of the supporting end of an arm. 55

Similar numerals refer to similar parts throughout the drawings.

The supporting bracket 1 may be provided with an axial pivot stem 2 journalled in a conical bearing 3 on the free end of 60 a swinging arm 4 journalled at its other end in the bearing 5 on the free end of a supporting arm 6, in well known manner.

The radial arms 7 of the bracket are inclined slightly upward toward their outer 65 ends 8, which ends are curved upwardly to form arcuate seats 9 for supporting and surrounding the correspondingly curved rim portion 10 of the tray 11, the bottom of which is suspended freely above the concave 70 intermediate portions of the supporting bracket.

Resilient radial ribs 12 are provided in the arcuate seats and are preferably in the form of upwardly curved rubber strips or 75 plates partially countersunk in corresponding radial slots 13 provided in the arcuate seats at the ends of the arms; and a substantial edge portion of each rib protrudes 80 from the arcuate seat so as to bear and clamp 85 around the rim portion of the tray, as shown in Fig. 2.

It is preferred to provide some six or more radial arms in the supporting bracket so as to firmly sustain the tray and prevent 85 a tilting thereof; and it is evident that the periphery of the rim portion of the tray will not only be cushioned and clamped by the radial ribs, but that the weight of the tray will so compress the contiguous portions of the ribs that the upper ends 14 thereof will clamp around the upper edge 15 of the rim of the tray and hold it firmly 90 in position, unless it is bodily lifted therefrom; the ends of the arcuate seats and resilient ribs being preferably extended above the edge of the rim, as shown in the drawings, to effect this clamping action. 95

I claim:—

A bracket for dental trays and the like, 100 having a plurality of upwardly curved radial resilient ribs partially countersunk in the bracket for bearing and clamping around the rim portion of the tray.

HENRY E. WEBER.
